UNITED STATES PATENT OFFICE.

CHARLES M. KIMBALL, OF BRADFORD, MASSACHUSETTS.

CRIMPING-MACHINE.

SPECIFICATION forming part of Letters Patent No. 331,795, dated December 3, 1885.

Application filed March 3, 1883. Serial No. 86,884. (No model.)

To all whom it may concern:

Be it known that I, CHARLES M. KIMBALL, of Bradford, in the county of Essex and State of Massachusetts, have invented a new and 5 useful Improvement in Crimping-Machines, of which the following is a specification.

My invention relates to an improvement in machines for crimping boot and shoe vamps, whereby I am enabled to crimp vamps of different forms in the same machine by simply reversing the motion of the rotating formers without changing any part of the machine.

The invention consists of a series of radial blades or formers, which are fixed in a wheel, 15 each former having its opposite edges of a different shape or outline. These formers are caused to rotate and pass between two jaws or plates, so as to carry the vamps always in one direction and deliver them from the machine 20 without reversing the motion of the formers when a form for a shoe-vamp only is required. When a different form for boot-vamps is required, the motion of the wheel carrying the formers is reversed, the operation in both 25 cases being continuous in one direction.

In order to insure the crimping of the entire vamp when the leather is thicker or thinner at different parts, I employ a series of plugs or plungers having their inner ends projecting slightly beyond the inner surfaces of 30 the plates or jaws, the plugs being forced outwardly by springs, and so disposed that every part of the vamp will come in contact with said plugs.

35 Referring to the accompanying drawings, Figure 1 is a side elevation of a machine embodying my invention. Fig. 2 is a vertical transverse section on the line $x-x$ of Fig. 1. Fig. 3 is an elevation showing the formers and 40 one of the plates or jaws as attached to the frame. Fig. 4 is a view of one of the plates or jaws. Fig. 5 is a detail view of spring and plug. Fig. 6 is a top view of the jaws, the wheel and formers being removed.

45 A is a bed or base supporting the iron frame of the machine. The frame is made in two parts, each consisting of the horizontal portion F, the perpendicular portion F', and the braces F'', as seen in Fig. 1. Between the two frames 50 is a cogged wheel, B, journaled in the upper portions, F, of the frame. The two parts of

the frame are secured together by bolts L at the ends K K K.

D D D D are four formers, composed of metal plates attached to or forming a part of the 55 wheel B and the hub H. The two edges of each former have a different contour, the edge marked d' being designed for crimping the vamps of shoes, and that marked d for crimping boot-vamps. On the inner side of 60 each portion of the frame and forming a part of the same is attached a semicircular plate, E, the upper edges, e e' , of which correspond in contour or outline with the edges d d' of the formers D and serve as jaws in receiving the 65 vamp.

The wheel B is rotated by means of a pinion, C, operated by any power applied to the crank C' or otherwise.

In the plates E E are holes f' , through which 70 project slightly beyond the inner surface of the plates the plugs or plungers f f' , so as to play freely. (See Fig. 2.) The outer ends of the plugs f are enlarged, so as to form shoulders bearing against the outer sides of the 75 plates E, to limit the play of the plugs. The plugs are held in place by means of springs g, which are attached at their opposite ends to screws i, having nuts h and bearing against the outer surface of the plates E. The springs 80 are held in place by small bars or rods G. (See Figs. 2 and 5.) The holes and plugs are so arranged in the plates as to cause the projecting ends of the plugs to come in contact with every portion of the vamp, so as to allow 85 for difference of thickness in different parts of the vamp. The nut on the screw i, against which the end of the spring g bears, admits of the adjustment of the spring to a greater or less tension in bearing upon the plug, as required. The distance between the plates E E may be adjusted to accommodate vamps of 90 different thicknesses by the bolts L, as desired.

In operation, when a shoe-vamp is to be crimped it is laid lengthwise over the jaws e e' . 95 The wheel B is then rotated in the direction indicated by the arrow 1, causing each former or plate D to force the vamp down between the jaws e e' and between the plates E E until it passes up between the jaws e e' on 100 the opposite side, and is there removed from the machine. A vamp is placed under the

edge d' of each plate D, the operation of crimping being continuous in one direction.

When a boot-vamp is to be crimped, it is laid upon the jaws $e e$ on the opposite side, the motion of the wheel B is then reversed, as indicated by the arrow 2, and the edges d of the plates or formers D force the vamp down between the jaws $e e$ and the plates E E, and up through the jaws $e' e'$, where they are removed from the machine.

It will thus be seen that I am enabled to crimp both a shoe and a boot vamp in one and the same machine without changing any of its parts, the change from one to the other being effected by simply reversing the rotation of the wheel and formers, and by forcing the vamps through and between the plates the surface over which they pass is greatly extended and the vamps are more effectually crimped.

I do not claim rotating trees and pressure-jaws for crimping boots and shoes, as I am aware that such are not new; but

What I do claim as my invention is—

1. In a crimping-machine, the semicircular plates E E, the upper edges, $e e'$, of which are made in outline, the one for crimping boots and the other for crimping shoes, in combination with the formers D, having edges $d d'$, corresponding, respectively, with those of the plates E E, whereby the formers as they are rotated in one direction will crimp a boot, and when rotated in the opposite direction will crimp a shoe, substantially as set forth.

2. In a crimping-machine, the plugs or plungers $f f$, held in position by adjusting-springs, in combination with the perforated plates E E, substantially as and for the purpose set forth.

In testimony whereof I have signed my name to this specification in the presence of two subscribing witnesses.

CHARLES M. KIMBALL.
